(57) **CLAIM**

We claim the ornamental design for a portable electronic device, as shown and described.

DESCRIPTION

FIG. 1 is a perspective view of a portable electronic device showing our new design in a folded position; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is an enlarged left side elevational view corresponding to that shown in FIG. 4; and, FIG. 9 is a perspective view of the portable electronic device in an unfolded position in use and shows that part of the rear cover is spread and used as the stand. The broken line in the figures represents unclaimed portions of the portable electronic device and forms no part of the claimed design.
